UNITED STATES PATENT OFFICE.

RUDOLPH W. HUSS, OF CHICAGO, ILLINOIS.

INCANDESCENT GAS-LAMP.

SPECIFICATION forming part of Letters Patent No. 739,314, dated September 22, 1903.

Application filed February 9, 1903. Serial No. 142,642. (No model.)

To all whom it may concern:

Be it known that I, RUDOLPH W. HUSS, a citizen of the United States, residing at Chicago, in the county of Cook and State of Illinois, have invented certain new and useful Improvements in Incandescent Gas-Lamps, of which the following is a specification.

My invention relates to gas lamps or burners, and particularly to gas lamps or burners of the class known as "incandescent gas-lamps" and involving a Bunsen burner, a chimney, and a mantle of suitable refractory material.

Objects of my invention are to facilitate the admixture of air and gas preparatory to combustion, to vary the length of the mixing-tube with reference to requirements and observed results, to provide a simple, compact, and economical construction, and to insure a light of great brilliancy.

In the accompanying drawings, Figure 1 shows in elevation an incandescent gas-lamp embodying the principles of my invention. Fig. 2 is a vertical central section of the lamp on a reduced scale, a portion of the mantle-support being broken away and the mantle being omitted for convenience of illustration. Fig. 3 shows the spirally-corrugated burner-tube detached from the spirally-corrugated sleeve.

A indicates a Bunsen burner comprising a tube having its lower end portion 1 provided with side openings 2 for the admission of air and inclosing a gas tip or nipple 3, which can be attached to any ordinary or suitable gas-fixture, such as illustrated by dotted lines in Fig. 1. The tube which thus receives a supply of gas from the nipple and a supply of air through its side openings is of sufficient length and transverse area to form an upright passage wherein the admixture of the air and gas is effected preparatory to combustion at a point where the fluid passes out through a wire-gauze screen or diaphragm 4, arranged at the upper end of the passage through the burner. The burner-tube is formed or provided with an upper end portion 5 of greater diameter than its lower portion 6, so as to form a passage portion of suitable area for the efficient mixing of the air and gas, or, in other words, a suitable length 5 of the tube is made of sufficient diameter to permit the

air and gas to properly mix together, while the lower tube portion 6 is relatively contracted with reference to well-known principles upon which burners of this class operate. The upper portion 5 of the burner-tube is spirally corrugated both internally and externally, whereby its outer surface forms a screw-thread corresponding with the internal screw-thread of a like spirally-corrugated sleeve B, while its interior surface presents, in effect, a vertical series of alternate lateral contractions and expansions, which serve to cause eddies in the ascending air and gas, and thereby insure more perfect admixture of the same. The sleeve B rises centrally from and is secured to the gallery or chimney-holder C, and as a simple and exceedingly economical construction the enlarged portion 5 of the burner-tube and the sleeve B, which in Figs. 1 and 2 forms a part of the burner, are made of sheet metal and spun or drawn with the spiral corrugations illustrated. The tube portion 6 may, as a matter of course, be also made of sheet metal, and the tube portions 5 and 6 can be primarily of one piece, although, if preferred, the upper tube portion can be made separate from the lower tube portion and be secured thereto, as in Fig. 5. The foraminated screen or diaphragm 4 can be secured to the top end of sleeve B, as in Fig. 2, in which the base end of the chimney-holder is understood to be unattached as to the burner-tube portion 6, and with this arrangement the conducting and mixing passage can be adjusted in length in accordance with conditions and requirements by relatively turning the burner-tube and the chimney-holder to which the threaded sleeve is secured, it being observed that when the burner-tube is not attached to a gas-fixture it can be screwed into or outwardly from the sleeve by turning either the tube or the sleeve and that when the tube is attached to a gas-fixture the length of the passage can be adjusted by turning the sleeve and that as a simple arrangement the sleeve can be rigid with the chimney-holder, whereby the operator can easily raise and lower the sleeve and the chimney-holder by merely turning the latter about a vertical axis. The gallery or chimney-holder is adapted to receive and support a chimney as usual, and it is also provided with a support D for

a refractory mantle E. The length of the spirally-corrugated portion of the burner-tube permits a wide range of adjustment in the length of the passage and forms an exceedingly simple and perfectly steady connection 5 between the chimney-holder and the portion of the burner which is attached to the gas-fixture, and it also permits the parts to be readily separated for purposes of cleaning. 10 Both the sleeve and the burner-tube can be corrugated at almost nominal expense, and in practice I have repeatedly demonstrated that with a lamp having my burner-tube corrugated a much more brilliant light is attained 15 than where the tube is not thus corrugated.

In the construction shown the spirally-corrugated tube-section 5 and the spirally-corrugated sleeve or tube-section B practically combine to form an adjustably-extensible 20 spirally-corrugated mixing-tube, whereof the tube-section 5 is arranged to extend centrally through the gallery C and also of a length to extend both above and below the point where the lower end or base of the chimney is supported. 25 By rotatively adjusting the tube-section B the length of the spirally-corrugated tube can be extended in accordance with requirements and observed results, such as the character and quality of the gas and the pressure 30 of the gas-supply, and where the sleeve or tube-section is secured to the gallery, as shown, the relative adjustments of the tube-sections B and 5 will, while varying the length of passage through the mixing-tube, also 35 raise or lower the gallery relatively to the base formed by parts 1 and 6 of the burner-tube, and thereby raise or lower both the chimney and the mantle.

What I claim as my invention is—

40 1. In a burner, a base having a centrally-located passage for gas; an adjustably-extensible mixing-tube having spiral corrugations above said gas-passage and having air-inlet openings at its base, opposite the gas-passage; 45 and a suitable burner at the top.

2. In a burner, a base having a centrally-located passage for gas; an adjustably-extensible mixing-tube having spiral corrugations

above said gas-passage and having air-inlet openings at its base opposite the gas-passage, 50 said adjustably-extensible mixing-tube being formed by two spirally-corrugated tube-sections adapted and arranged to screw the one upon the other; and a suitable burner at the top. 55

3. In a burner consisting of an incandescent gas-lamp constructed with a body forming a chimney-holder and provided with a support for a refractory mantle, a base having a centrally-located passage for gas; an adjustably-extensible mixing-tube having spiral corrugations above said gas-passage and having air-inlet openings at its base opposite the gas-passage, 60 said adjustable extensible mixing-tube being formed by two spirally-corrugated tube-sections adapted and arranged to screw the one upon the other, one of such tube-sections being provided at its upper end with a burner and being secured to the body which forms the chimney-holder. 65

4. In an incandescent gas-lamp, a gallery forming a chimney-holder and provided with a support for a mantle; a centrally-arranged, spirally-corrugated mixing-tube composed of a couple of spirally-corrugated tube-sections 70 screwed the one upon the other, one of said tube-sections being provided with a burner and secured to the gallery, and a base below the mixing-tube and forming a gas-passage having a lateral inlet-opening for the admission of air, 75 said base being extended upwardly by the inner one of said spirally-corrugated tube-sections. 80

5. In a gas-lamp, a gallery forming a chimney-holder; a spirally-corrugated sleeve or tube-section B secured to the gallery and provided at its top end with a suitable burner; a spirally-corrugated tube-section 5 arranged to screw within the tube-section B; and a tubular base extended downwardly from the 85 spirally-corrugated tube-section 5 and having a lateral opening for the admission of air. 90
